COMBINED TAIL LIGHT AND SUPPORT BRACKET FOR BOAT TRAILERS

James A. Driscoll, 1219 Garfield,
Sand Springs, Okla. 74063

Filed Apr. 22, 1974, Ser. No. 462,607

Term of patent 14 years

Int. Cl. D26—06

U.S. Cl. D48—32 R

FIG. 5

FIG. 1

FIG. 2

FIG. 3

FIG. 4

FIG. 6

FIG. 1 is a front elevational view of a combined tail light and support bracket for boat trailers, showing my new design.

FIG. 2 is a elevational view of one side.

FIG. 3 is a rear elevational view.

FIG. 4 is an elevational view of the other side.

FIG. 5 is a top plan view.

FIG. 6 is a bottom plan view.

I claim:

The ornamental design for a combined tail light and support bracket for boat trailers, substantially as shown.
